Primary Examiner — Janice Hallmark

(57) **CLAIM**

The ornamental design for a rack for storing cell phones and CDs, as shown and described.

DESCRIPTION

FIG. 1 is a perspective view of a rack for storing cell phones and CDs, showing my new design;

FIG. 2 is a front view thereof;

FIG. 3 is a bottom view thereof;

FIG. 4 is a top view thereof;

FIG. 5 is a rear side view thereof;

FIG. 6 is a left side view thereof; and,

FIG. 7 is a right side view thereof.

The broken lines illustrate portions of the rack for storing cell phones and CDs that form no part of the claimed design.

1 Claim, 7 Drawing Sheets
